UNITED STATES PATENT OFFICE.

ARTHUR SHELBYNE AND WILLIAM A. BUETTNER, OF SULLIVAN,
INDIANA.

CUTTER-HEAD.

SPECIFICATION forming part of Letters Patent No. 788,734, dated May 2, 1905.

Application filed July 22, 1904. Serial No. 217,735.

To all whom it may concern:

Be it known that we, ARTHUR SHELBYNE and WILLIAM A. BUETTNER, citizens of the United States, residing at Sullivan, in the county of Sullivan and State of Indiana, have invented certain new and useful Improvements in Cutter-Heads; and we do hereby declare the following to be a full, clear, and exact description of the invention, such as will enable others skilled in the art to which it appertains to make and use the same.

Our invention relates to coal-mining machines, and more particularly to means employed for mounting the endless tool-carrier whereby the parts will be protected against wear and the cost of maintenance reduced to a minimum; and our invention consists of certain novel features of construction and combination of parts, the preferred form whereof will be hereinafter clearly set forth, and pointed out in the claims.

The prime object of our invention, therefore, may be said to be the provision of protecting bearing-seats for the wheels employed in carrying the endless chain, which latter is provided with a plurality of cutting tools or blades, as is common.

Other objects and advantages will be hereinafter made clearly apparent, reference being had to the accompanying drawings, which are made a part of this application, and in which—

Figure 1 shows our cutter-head complete ready for use with a portion of the tool-carrying chain operatively disposed relative thereto. Fig. 2 is an edge view of the cutter-head. Fig. 3 is a section of Fig. 1, taken on line 3-3. Fig. 4 is a sectional view taken on line 4-4 of Fig. 2. Figs. 5 and 6 show the inner side of the two complementary sections composing the cutter-head. Fig. 7 is a central sectional view of the carrier wheel or idler employed to carry and direct the endless chain to which is connected a plurality of coal-cutting tools. Fig. 8 is a longitudinal section of the member employed by us in securing perfect lubrication for the carrying-wheel illustrated in Fig. 7.

For convenience of reference to the various

details and coöperating accessories numerals 50 will be employed, the same numeral applying to a similar part throughout the several views.

In this connection it may be briefly stated that our cutter-head is so constructed that the chain-carrying wheels mounted therein 55 will have their bearings completely isolated or inclosed, whereby said wheels will always run in oil or in a perfectly-lubricated condition free from dust, grit, and consequently free from liability to become worn and deteriorated, the two parts of our cutter-head 60 serving as a reliably efficient guideway for the endless tool-carrier, whereby the tools will be reliably held to the performance of their office, thus so directing the tools that 65 no lost motion thereof can result or unnecessary work placed upon them.

For the purposes of this application we deem it unnecessary to show an entirely complete machine or how the power is applied, it being 70 understood that power may be applied in any preferred way, and we will therefore call attention to the showing made in the drawings, wherein it will be observed that special construction has been employed to not only provide 75 non-wearing dust-proof bearings, but also to provide means for compensating for undue wear upon certain portions of the cutter-head.

Referring in detail to the drawings, 1 indicates the top section, while 2 designates the bottom section, said members being complementary to each other and are designed to be bolted securely in union, as by entering bolts through suitable apertures 3 in the member 1, 85 the threaded ends of said bolts being seated in threaded holes 4 provided in the bottom section. It will be further observed that a wheel-seat is formed in each end of each of said complementary members, the said wheel-seat being of special form, as will be herein-after particularly set forth. Each of the members 1 and 2 is also provided, respectively, with a raised portion or rib 5 and 6, having ground faces, whereby they will engage each other and form an absolutely tight joint or fitting.

The wheel-seats in each end of the members

1 and 2 are adapted to receive a special form of chain-carrying wheel, as shown in Fig. 7, and attention is therefore called to Fig. 3 of the drawings, wherein it will be observed that 5 the member 2 is provided at each end with a collar-like extension or flange 7, within which the hub 8 of the wheel 9 is designed to rotate, it being observed that an annular space 10, surrounding the collar 7, is provided to accommodate the bell-shaped flange of said wheel. As best shown in Figs. 3 and 7, the inside of the hub 8 is provided with a flange-bushing 8^a, which tends to reduce wear and exclude grit, &c., from the bearing. It will further- 15 more be observed that a socket is provided centrally at the bottom of the flange 7 to receive the trunnion or journal 11 of the tubular axle or shaft 12, said axle being hollowed out in order to be filled with oil or other form 20 of lubricant, which latter is free to pass out of a plurality of apertures 13, more clearly shown in Fig. 8.

It will be observed that the central or body portion of the member 12 is of larger diameter 25 than its outer end 14, which latter serves as a journal and enters a suitable opening provided in a contiguous part of the member 1, and it is therefore obvious that when the complementary members 1 and 2 are bolted together 30 the wheel 9 will be provided with a reliable form of axle upon which to rotate, and since said axle is tubular, as before explained, and normally full of oil, the friction incident to the rotation of the wheel will be reduced to a 35 minimum. It therefore becomes desirable to provide means for completely isolating and protecting the axle or supporting member 12 and rendering the same absolutely dust-proof, and with this purpose in view we form upon 40 the top section 1 an annular rib 15, having a ground face, which latter is designed to bear directly against the ground face 16 of the wheel 9, a corresponding annular recess being also provided on the inner side of the rib or 45 flange 15, designed as a seat for the gasket 17, which fits snugly around the terminal 14, and since said gasket is held in place against being crushed by means of the annular flange 15 it follows that said gasket will prove a 50 reliably efficient barrier against the passage of dust, grit, or the like into the bearing of the carrying-wheel 9, thereby insuring that said carrying-wheel will not only be reliably supported in its operative position, but that the 55 bearings thereof will always be in oil or a perfectly-lubricated condition.

By reference to Fig. 6 it will be seen that the bottom member is so formed that it will be provided with extensions 18, whereby it 60 may be bolted to the chain-guide attached to the other cutter-head or working parts. Said bottom section is also formed with the extensions 19, designed to be bolted to connecting-bars, as will be obvious, whereby the cutter-head may be reliably controlled, as usual.

By reference to Figs. 5 and 6 it will furthermore be seen that each of the members 1 and 2 is provided with a compensating bar 20, preferably formed of tool-steel and of proper size not to entirely fill the space between the 70 members 1 and 2, the object in thus leaving a slight clearance between them being to compensate for expansion incident to the use of the machine inasmuch as burs or irregularities in the surface and edges thereof will be 75 produced as the endless chain or carrier travels over the same. Cutter-heads as ordinarily constructed of two complementary members have no provision made to compensate for the mashing down or the production of burs incident to the travel of the chain over the exposed surface thereof, and the result is that the complementary sections are spread apart and disturb the bearings and soon unfit the cutter-head for further efficiency. 80 85 85

The outer edge 21 of the member 1, it will be understood, does not contact with the outer edge 22 of the member 2, sufficient space being left between them, as shown in Fig. 2, to receive the links 23 and the necks or extensions 24 of the tool-carrying members 25 common to coal-cutting machines, it being understood that the space left between the edges 21 and 22 may be regulated as desired. 90

It will thus be seen that we have provided 95 reliably efficient means for mounting the tool-carrying chain, whereby it may be driven with the least possible friction.

The various parts of our invention may be manufactured at a comparatively small cost 100 and each part readily assembled in its respective operative position, and while we have described the preferred combination and construction of parts we desire to comprehend in this application all substitutes and equivalents 105 that may be considered as falling fairly within the scope of our invention.

When it is desired to hold the member 12 against rotation, the journal 11 may be provided with a transverse aperture to receive a 110 locking bolt or rivet 26, as shown in Fig. 3, said terminal 11 being preferably formed with a concavity, as designated by the numeral 27, to facilitate the boring of a hole for the reception of said locking-rivet. The member 1 115 is also tapped at each end, as designated by the numeral 28, through which a plug or closure 29 may be entered in the tubular end of the extension 14, said plug being easily removed and secured in place after the tubular 120 axle has been filled with oil or other lubricant.

Believing that the advantages and manner of constructing and using our invention have thus been made clearly apparent, further description is deemed unnecessary. 125

What we claim as new, and desire to secure by Letters Patent, is—

1. The herein-described cutter-head comprising the complementary members 1 and 2, each formed with the semibearing-seat com- 130

plementary to each other on opposite sections, said seat comprising in the bottom sections a flange or collar 7 and upon the top section an inwardly-directed flange 15; a chain-carrying wheel having a hub-like member or extension 8 fitting within the flange of the member 2 and engaged at its upper end by said flange 15; a tubular journal having a plurality of apertures piercing the wall thereof operatively mounted in suitable bearing seats or sockets of the complementary members; suitable means for securing the complementary members 1 and 2 in union with each other; removable compensating bars 20 carried by each of said members and means to hold said bars in union with each other and with controlling parts thereof, all combined substantially as specified and for the purpose set forth.

2. The herein-described cutter-head comprising members 1 and 2, semibearing-seats for each section, a chain-carrying wheel having a hub, said hub fitting within the semibearing-seat of the member 2, a tubular journal having a plurality of apertures piercing the wall thereof mounted in suitable bearing-seats in said members 1 and 2, means for securing the members 1 and 2 together, all combined substantially as set forth.

3. The herein-described cutter-head comprising the members 1 and 2, each member being provided with semibearing-seats, the seat in the member 2 comprising a flange or collar 7 and the seat in the member 1 a flange 15, a chain-carrying wheel having a hub-like member fitting within the flange 7 and engaged at its upper end by the flange 15, a space being left between said semibearing-seats to accommodate the bell-flange of said wheel, a

tubular journal for said chain-carrying wheel having a plurality of apertures piercing the walls thereof, removable means to close the upper end of said tubular journal, and additional means to hold said journal stationary, all combined substantially as and for the purpose set forth.

4. In a cutter-head, the combination with members 1 and 2 having semibearing-seats and a chain-carrying wheel mounted therein, of a tubular journal having its upper and lower ends reduced in size, also having a plurality of apertures piercing the walls thereof, a closure for the upper end of said journal, and means to engage the lower end of said tubular journal and hold the same from rotation, as set forth.

5. In a cutter-head, the combination with members 1 and 2 each having semibearing-seats, of a chain-carrying wheel having a hub-like member or extension and a bell-shaped flange, said carrying-wheel being engaged by the semibearing-seats of the members 1 and 2, a tubular journal fitting within said hub-like member, a gasket surrounding the upper end of said tubular journal and the flange-bushing interposed between said journal and the hub of said carrying-wheel, substantially as set forth.

In testimony whereof we have signed our names to this specification in the presence of two subscribing witnesses.
